Benjamin Garvey

UNITED STATES PATENT OFFICE.

BENJAMIN GARVEY, OF NEW YORK, ASSIGNOR TO HIMSELF AND JOSEPH B. DAVOL, OF BROOKLYN, NEW YORK.

IMPROVED STEAM-GENERATOR.

Specification forming part of Letters Patent No. 29,217, dated July 17, 1860.

To all whom it may concern:

Be it known that I, BENJAMIN GARVEY, of the city, county, and State of New York, have invented a new and Improved Form of and Mode of Working a Steam-Generator; and I do hereby declare the following to be a full, clear, and exact description of the form of and mode of working same, reference being had to the accompanying drawings, making a part of this specification, in which—

A is a "couple" or cell formed of two thin sheets of metal riveted together with rivets so close one to another that these two thin sheets of metal or sides of a couple are held together with a greater force than the steam to be generated between them is calculated to exert. The space between the sides of any couple is sufficient to receive a thin film only of water or of steam, and the thickness of the sheets of metal which I select to form the sides of a couple is the least which will give adequate strength; also, the metal which I select for these thin sheets is the best conductor of heat which any given circumstances will allow, in order that the water or steam within the couple may be in as direct and intimate connection with the source of heat as possible.

B represents a force-pump, which for illustration's sake is given as a representative of any and every means of forcing water into the couple, and for the same reason is shown in direct connection with one couple.

C is the suction - pipe of the force - pump, by which the latter draws water from a condenser, tank, or other source of supply.

D is a pipe by which the steam passes off for use.

To enable others skilled in the arts to make and use my invention, I describe its construction and operation, as follows:

To form one couple, I take two thin sheets of metal and secure them around the edges by any of the well-known devices for that purpose, leaving an opening at one corner for an inlet-pipe and another opening at another corner for an outlet-pipe. I then rivet the two sides of the couple together with rivets at short distances apart, for common use selecting one inch as the measure of such distance. I arrange one or several such couples in the smoke-box of a furnace, vertically, horizontally, or at any angle with the horizon. I next

connect the inlet-opening or inlet-openings with a feed-pipe having, when several couples are used, a cock which will allow the feed-water to go to any one or more of the couples at a time, as may be desired. I also connect the outlet - opening or outlet - openings with a steam-pipe having, when several couples are used, a cock which will allow the steam to pass off for use from any one couple, or from several couples at the same time, as may be required.

The operation of this generator is as follows: When a charge of water is thrown by a force-pump, or any equivalent means, into one couple, or into several couples at the same time, the cock or other well-known device for such purpose is so turned that the connection between the feed-pipe and the charged couple or couples is broken; also, the cock or other equivalent device through which the couple or couples is connected with the steam-pipe is turned, so as either to make or break the connection, as may be desired, so that the steam generated within the couples may pass off as fast as it is formed, or may be held until it is superheated to any degree desired. The means whereby these cocks are operated is not shown, because there is no one way which will answer under all circumstances, and there are several ways of operating cocks or equivalent devices which will answer for all cases in practice; also, when the steam is intended to pass off as rapidly as it is generated, there is no steam or water cock required—only a regulated feed of water; but in no case do I employ a reservoir of steam or of hot water. In working a steam-engine the couple or couples which are at any time put in connection with the cylinder are entirely emptied by one stroke of the piston, and to generate a fresh charge of steam by the same couple or couples another charge of water is injected by the force-pump, &c. The object of using more couples at one time is merely to enable a generator of small size to be employed for supplying a large cylinder with steam, or to allow sufficient time to the charge of water in any couple to be heated sufficiently before being converted into working-steam.

I do not confine myself to the specific form herein described, but sometimes form a couple by means of tubes of very small bore and

thin substance. These tubes I screw or rivet into a small water-pipe at one end and a small steam-pipe at the other, and in such cases I generally flatten the sides of the tubes, so that there shall be only a film of water or steam between them. I then use couples formed in this way exactly in the same manner as those formed in the first-described manner, allowing the products of combustion to circulate around them, so that the water and steam within may be in as intimate connection with the source of heat as possible.

What I claim as my invention, and desire to secure by Letters Patent, is—

The form of steam-generator herein substantially described, when employed as specified.

BENJAMIN GARVEY.
